N. 2962

William S. Barn

Design for the following Bath and Closets

PATENT
NOV. 31

United States Patent Office.

WILLIAM S. CARR, OF NEW YORK, N. Y.

Design No. 2,962, dated March 31, 1868.

DESIGN FOR THE CONTAINER OF WATER-CLOSETS.

The Schedule referred to in these Letters Patent and making part of the same.

TO ALL WHOM IT MAY CONCERN:

Be it known that I, WILLIAM S. CARR, of the city and State of New York, have invented and produced a new and original Design for the Container of Water-Closets; and I do hereby declare the following to be a correct description of the said design, reference being had to the annexed photographic view of the same.

The shape of the container on the side *a* somewhat resembles an egg-shell divided longitudinally and transversely into quarter sections, one of said sections forming the shape of that side.

The side *b* resembles, in general shape, a section of a spheroid, extending out as shown; the parts *a* and *b* being united by curves, as represented.

The container is hollow, and the upper open portion is shaped with an inward flange, *c*.

At *d* the container is shaped angularly, at the point where the angle of the swinging pan of the closet is contained.

e is a three-armed base upon which the closet stands.

f represents the shape and configuration of a flange that I sometimes employ for receiving the cock of the closet; but this part does not form any portion of my present new and original design.

What I claim, and desire to secure by Letters Patent, is—

The design of the shape and configuration of the container of a water-closet, as represented.

In witness whereof, I have hereunto set my signature, this twenty-ninth day of February, A. D. 1868.

WM. S. CARR.

Witnesses:

GEO. D. WALKER,

CHAS. H. SMITH.
